UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,966, dated July 1, 1890.

Application filed April 15, 1890. Serial No. 348,094. Term of patent 3½ years.

To all whom it may concern:

Be it known that I, HENRY A. WEIHMANN, a citizen of the United States, residing in Philadelphia, in the county of Philadelphia and State of Pennsylvania, have invented and produced a new and original Design for Cane or Umbrella Handles, of which the following is a specification, reference being had to the accompanying drawing, forming part thereof.

10 In the drawing is shown a perspective view of a cane or umbrella handle illustrating my new design.

15 A is the body part, and swells both at top and bottom, but more at the top than at the bottom, and has a plain surface, excepting upon portions of its sides, which are ornamented, as indicated at D. In practice there are three of these ornamentations, and the upper portions of said ornamentations continue over the top of the body part A and into the depressed head B, as indicated at C, uniting at the center.

F is the base part, arranged below the body part and separated from it by an ornamental band E, and said base part is also ornamented 25 by points or otherwise, and is substantially of the shape shown, and, furthermore, this base part is bounded on the bottom by an annular band G of plain surface.

The handle is made of any suitable material.

Having now described my new design, what I claim as new, and desire to secure by Letters Patent, is—

The design for cane or umbrella handles, 35 substantially as herein described and shown.

In testimony of which invention I have hereunto set my hand.

HENRY A. WEIHMANN.
